SEPARABLE ELECTRICAL CONNECTER

Filed Sept. 29, 1923

FIG. 1.

FIG. 2.

FIG. 3.

FIG. 5

Inventor:

A. L. Lawrence

UNITED STATES PATENT OFFICE

ALBERT LYNN LAWRENCE, OF CLEVELAND, OHIO

SEPARABLE ELECTRICAL CONNECTER

Application filed September 29, 1923. Serial No. 665,726.

My invention relates to improvements in separable electrical connectors and has for its object the provision of means in association with such connectors whereby they may 5 be more readily connected or assembled for closing the controlled electric circuit.

The most common form of separable electrical connector is of the type which has a screw-threaded base adapted to be inserted 10 in a wall or baseboard socket, and a co-acting plug-member having terminals designed to be inserted within suitable contact-containing receptacles in said base. I shall explain my invention as applied to a separable connector of this type, although it is not necessarily limited to the structural features herein shown and described, except as they are defined in the appended claims.

A difficulty commonly met with in the use 20 of separable electrical connectors resides in the repeated effort frequently found necessary in aligning the terminals of the plug-member with their receptacles so that connection may be established. The base or wall 25 socket in which the plug-member may be inserted quite often is in a dark corner or in an awkward position so that the location of the relatively small receptacles for the terminals of the plug may not be determined 30 readily, hence some delay and difficulty is encountered in inserting the plug. Indeed, the advantages of a separable plug connector frequently are not availed of and the device is screwed as a whole into the socket, because 35 of the difficulty above referred to.

Accordingly, I have provided means for 40 readily aligning the two members of a separable connector that preferably conform to standard specifications and sizes, while increasing the expense of manufacture in no material respect. Such means may comprise 45 a positive terminal-stop or abutment in association with a receiving opening and with or without guiding grooves for the terminals, or such centering means may comprise one or 50 more flaring or tapered grooves leading to the contact receptacles, which grooves are adapted to align the terminals with such receptacles upon partially rotating the plug-member. The details of my improvements,

however, may best be explained by making reference to the accompanying drawings, wherein:

Figure 1 is a view of a separable plug-member with an attached section of connecting 55 cord; both shown in elevation,

Fig. 2 is a plan view of the associated base-member constructed in accordance with one modification of my invention,

Fig. 3 is an irregular vertical section on 60 line 3—3, Fig. 2,

Fig. 4 is a plan view of a modified form of base-member approximating the type of Fig. 2,

Fig. 5 is a view partly in elevation and 65 partly in section on line 7—7, Fig. 2 illustrating the connected plug and base members.

The same character of reference is employed throughout the several figures of the 70 drawings to indicate similar parts.

In accordance with my invention, it will be observed that one or both members of the separable electrical connector, otherwise of well known type, are modified for the purpose of guiding the protruding terminals 75 to their respective contact-holding receptacles. This ordinarily is accomplished by approximately a quarter turn of the separable plug-member with respect to the inserted 80 base-member; the terminals readily finding and seating themselves in engagement with their respective contacts.

The types specifically shown in Figs. 2, 3 and 4 require the modification merely of the 85 female or base-member of the connector, so that the terminals themselves are guided into alignment with their respective receptacles in said base-member merely by rotating the plug-member with the ends of the terminals 90 engaging the slotted surface of the base-member. Thus, in the type specifically shown in Figs. 2 and 3, there are provided two shallow tapering grooves e' , e'' wider at their diametrical or upper ends and narrowing down 95 to the respective receptacles b' , b'' whose further walls form stops adapted to arrest, respectively, the terminals guided thereto. A partial turn of the plug-member, accordingly, will serve to bring the terminals into 100

accurate alignment through the engagement of their ends with the walls of the slots or grooves and permit their ready insertion into the contact-holding receptacles b' , b'' .

5 The modification shown in Fig. 4 provides two similar flaring grooves f' , f'' , with which one of the terminals is adapted to be engaged and, upon turning the plug in either direction, the two terminals will be brought into 10 alignment with their respective receptacles and one or the other of the side walls of said receptacles will serve as a stop to assist the insertion of the terminals when thus aligned with their respective receptacles.

15 It will be appreciated that the openings of the contact-containing receptacles preferably are made of small size to prevent the entrance of dirt or any short circuiting metallic part. Accordingly, it is desirable to 20 provide positively acting centering means, such as herein shown, and in association with a stop or stops for the terminals, afforded by the substantially radial vertical walls, to facilitate their insertion within the closely 25 embracing receptacles.

Having now described types of separable electrical connectors, each embodying my invention, I claim as new and desire to secure by Letters Patent, together with such structural departures therefrom as may be made by those skilled in the art, the following:

1. In a separable electrical connector, the combination with the plug-member, of protruding electric terminals spaced apart and 35 extending therefrom, a base-member having contact-containing receptacles positioned to receive said terminals when the two members are assembled, the opposite diametrical walls of said receptacles being higher respectively than their opposing walls within the 40 receptacles, and means for bringing the members into axial alignment with the terminals arrested against the walls of said receptacles upon the relative rotation of said members, substantially as set forth.

2. In a separable electrical connector, the combination with a plug-member, of protruding electrical terminals spaced apart equidistant of the axis of said member and 50 extending substantially parallel therefrom, a base-member having contact-containing receptacles positioned to receive said terminals when the two members are assembled; the upper face of said base-member having inclined and outwardly expanded grooves of 55 greater radial dimension than the spaced terminals, respectively meeting said receptacles at a level below the diametrically positioned vertical walls of the receptacles, whereby 60 these higher diametrical walls of said receptacles afford stops for entering the terminals within their respective receptacles upon rotating the plug-member axially, substantially as set forth.

65 3. In a separable electrical connector, the

combination with the plug-member, of protruding electric terminals spaced apart and extending therefrom, a base-member having contact-containing receptacles positioned to accommodate said terminals when the two members are assembled; said base-member having a downwardly inclined groove extending to a receptacle below the level of the opposite wall of said receptacle forming a stop terminating said groove, substantially as 75 set forth.

4. In a separable electrical connector of the class described, the combination with the plug-member, of protruding electric terminals spaced apart and extending therefrom, 80 a coacting base-member having contact-containing receptacles similarly spaced to accommodate said terminals when the two members are assembled; said base-member having inclined and rearwardly flaring grooves in 85 its upper face respectively cutting opposite side walls of the receptacles below the levels of the respective opposing walls, whereby the terminals are guided into alignment with said receptacles and arrested in position for 90 insertion therein, substantially as set forth.

5. In a separable electrical connector, the combination with the plug-member, of protruding electric terminals spaced apart and extending therefrom in diametrical relation, 95 a base-member having contact-containing openings similarly positioned to receive said terminals when the two members are assembled; a vertical radial wall of an opening being higher than its opposing wall to form 100 a stop, and means for guiding a terminal into arresting engagement with said higher vertical wall of such opening upon the relative rotation of said members, substantially as set forth.

In testimony whereof I have subscribed my name at Cleveland, Ohio, this 26th day of September, A. D., 1923.

ALBERT LYNN LAWRENCE.
